US00D802830S

(12) **United States Design Patent** (10) **Patent No.:** **US D802,830 S**
Stanley (45) **Date of Patent:** **** Nov. 14, 2017**

(54) **LIGHT FIXTURE**

(71) Applicant: **IP Holdings, LLC**, Vancouver, WA (US)

(72) Inventor: **John Stanley**, Vancouver, WA (US)

(73) Assignee: **IP Holdings, LLC**, Vancouver, WA (US)

(**) Term: **15 Years**

(21) Appl. No.: **29/596,622**

(22) Filed: **Mar. 9, 2017**

Related U.S. Application Data

(63) Continuation of application No. 29/578,431, filed on Sep. 21, 2016, now Pat. No. Des. 786,490, which is (Continued)

(57) **CLAIM**

The ornamental design for a light fixture, as shown and described.

DESCRIPTION

FIG. 1 is a perspective view of a first embodiment of a light fixture, as viewed from below, showing my new design; FIG. 2 is a perspective view of the light fixture shown in FIG. 1, as viewed from above; FIG. 3 is a left side view of the light fixture shown in FIG. 1; FIG. 4 is a right side view of the light fixture shown in FIG. 1; FIG. 5 is a front elevation view of the light fixture shown in FIG. 1; FIG. 6 is a rear elevation view of the light fixture shown in FIG. 1; FIG. 7 is a top plan view of the light fixture shown in FIG. 1; and, FIG. 8 is a bottom plan view of the light fixture shown in FIG. 1.

The broken-line disclosure shown in the views is understood to represent portions of the article in which the claimed design is embodied, but which form no part of the claimed design.

1 Claim, 6 Drawing Sheets

Related U.S. Application Data

a continuation of application No. 29/522,849, filed on Apr. 2, 2015, now Pat. No. Des. 770,079, which is a continuation-in-part of application No. 13/533,189, filed on Jun. 26, 2012, now Pat. No. 9,335,038.
